PINKING MACHINE

Victor J. Sigoda, Great Neck, N. Y., assignor to
 Man-Sew Pinking Attachment Corp., New York,
 N. Y., a corporation of New York

Application November 25, 1940, Serial No. 366,958

18 Claims. (Cl. 164—64)

This invention relates to pinking machines, and more particularly to a machine of that general type disclosed in my Patent No. 2,159,716 issued May 23, 1939, in which the pinking wheel or cutter is mounted to rotate in a horizontal plane and which is provided with means for automatically and positively feeding the fabric material to the cutting teeth of said wheel.

It is the general object and purpose of my present invention to simplify and improve the prior patented machine, whereby a marked reduction in manufacturing cost is obtained and greater efficiency in practical operation realized.

More particularly, in attaining the above mentioned results, the present invention is primarily characterized by the provision of means constituting a driving connection between the horizontally rotating cutter wheel and the relatively movable fabric feeding member, whereby operative motion is transmitted from the former to the latter. In a preferred embodiment of the invention, I provide a single element in direct driving connection between the cutter wheel and feed member.

It is also a further object of the invention to provide a novel combination and arrangement of the several parts with improved drive gearing for the cutter wheel, whereby the accumulation of fine lint upon the meshing teeth of the gear elements is obviated or markedly reduced.

Another object of the invention is to provide means for deflecting the larger particles of waste material from the path of rotation of the teeth of the cutter wheel.

It is also a further object of the invention to provide a pinking machine of the above type which will be positive and reliable in practical operation, of long life, and in which maintenance costs are reduced to a minimum.

With the above and other objects in view, the invention consists in the improved pinking machine and in the form, construction and relative arrangement of its several parts, which will hereinafter be more fully described, illustrated in the accompanying drawing and subsequently incorporated in the subjoined claims.

In the drawing wherein I have disclosed one simple and practical embodiment of the invention, and in which similar reference characters designate corresponding parts throughout the several views:

Fig. 1 is a top plane view, certain parts being broken away, illustrating a pinking machine embodying the present improvements.

Fig. 2 is a longitudinal sectional view taken substantially on the line 2—2 of Fig. 1, and

Fig. 3 is a transverse sectional view taken on the line 3—3 of Fig. 2.

Referring in detail to the drawing, 5 designates a base plate of suitable dimensions having depending longitudinal side flanges 6 integrally cast therewith and adapted to be fitted within an opening in a work-bench or table (not shown). 10 Any suitable means may be employed for the purpose of removably and rigidly securing said base plate in position upon the bench or table.

There is also provided upon one end of the base plate 5, and preferably integrally cast therewith, 15 a superstructure 7, the lengthwise dimension of which is disposed longitudinally of the base plate. This superstructure is formed with spaced transverse walls or webs 8 and 9 respectively, the latter of which is formed with a suitable bearing 10 for 20 the shaft 11 to the outer end of which the power driven wheel 12 is fixed. The superstructure 7 is formed at the top and front side thereof which a guard flange 13 for said drive wheel.

To the other or inner end of the shaft 11, a 25 gear or pinion 14 is fixed and is engaged with the teeth of a similar gear 15, secured to the shaft 16 journaled in spaced bearings suitably formed on the under side of the base plate 5. The spaced depending parts of the base plate in which the 30 shaft 16 is mounted are substantially continuations of the walls or webs 8 and 9, and together with the latter form an enclosure or housing for the gearing. The lower end of this housing is closed by the cap member 17 which forms a receiving sump for lubricating oil introduced through the opening 18 at the top of the superstructure 7, and through which the gear element 15 rotates.

The base plate 5 at the inner side of the above 40 described gearing is provided with a circular opening 19 to receive the cutting or pinking wheel 19 which is provided on its upper surface and at its outer edge with a continuous annular series of pinking teeth 20. This pinking wheel is 45 rigidly secured to the hub portion 21 of a worm gear 22 by means of the screws indicated at 21'.

One of the flanges 6 is connected to the base 50 plate 5 by the transverse bar 23 integrally cast therewith. The horizontal portion of this bar is suitably spaced below the base plate and is formed with the bearing portion 24 in which suitable anti-friction rollers 25 are interposed between the wall of said bearing portion and the periphery of the spindle 26 which is integrally 55 formed with the worm gear 22. The inner end of

the shaft 16 is provided with the worm 27 in mesh with the teeth of said worm gear. Preferably, a bridging web 28 connects the bearing 24 with the adjacent side wall of the housing for the gear 15.

The opposite side of the bearing 24 is formed with a seat extension 29 for the reduced end of a stud shaft 30. A cap piece 31 secured upon said stud extension encloses the upper portion of said shaft end which is rigidly fixed against rotation by a suitable set screw indicated at 32.

Upon the stud shaft 30 there is mounted for free rotation a drive member 33 for the fabric feeding disk 34. This drive member at one side thereof is formed with the hub or sleeve extension 35 projecting through a central opening in the disk 34 of appreciably greater diameter than said hub. This disk is also of greater diameter than the drive member 33 and projects upwardly and closely adjacent to the teeth 20 of the pinking wheel 19, through a slot or opening 36 in the base plate 5 disposed transversely thereof and in tangential relation to the opening 19. The drive member 33 at its upper side has frictional bearing contact with the lower surface of the pinking wheel 19, though, it will be understood that if desired, said member and wheel may be provided with inter-engaging teeth for the positive transmission of rotation to the member 33 from said pinking wheel. Preferably, suitable anti-friction rollers, indicated at 37, are interposed between the member 33 and its hub 35 and the stud shaft 30.

The end of the hub 35 is exteriorly threaded to receive the adjusting nut 38 for the resiliently yieldable spider 39, the arms of which have bearing contact against one side of the disk 34 to yieldingly urge the opposite side thereof into frictional contact with the opposed face of the drive member 33.

To the upper surface of the base 5 a sheet metal cloth guide plate 40, secured by one or more screws 41, is provided with a circular opening 42 registering with the opening 19 in the base plate and also provided with the slot 43 which registers with the slot 36 in the base plate. At the outer side of this slot the plate is formed with the downwardly inclined flange 44 having its free edge closely adjacent to the face of the feed disk 34. This flange provides a yieldable support for fabric seams as they pass beneath the pressure roller, to be presently described. It will be noted from reference to Fig. 2, that the upper surfaces of the plate 40 and of the cutting wheel 19 are disposed substantially in a common horizontal plane.

The superstructure 7 also includes a relatively narrow neck portion 45 extending longitudinally of the base plate, inwardly over the pinking wheel 19 and in vertically spaced relation above the same. This neck terminates in a vertically disposed guide sleeve 46 for the cylindrical shank of a yoke 47 extending upwardly therefrom into the lower end of the sleeve 46. An adjusting screw 48 is threaded in the upper end of said sleeve and a spring, indicated at 49, is interposed between said screw and the shank of the yoke 47. In said yoke the pressure roller 50 is revolvably mounted and has peripheral bearing contact with the teeth of the pinking wheel 19 and with the periphery of the feed wheel 34. Preferably, the periphery of said feed wheel is knurled or milled to afford a positive feeding engagement with the fabric materials.

Any suitable system of lubrication may be pro-

vided for the anti-friction bearings 25 and 37, such as the arrangement of ducts or passages illustrated in dotted lines, which are supplied with the lubricant through a central valved orifice indicated at 51 in the pinking wheel 19.

The plate 40 carries the vertically disposed cloth guide member 52. This member has a slotted base flange 53 receiving a threaded stud on the plate 40 and adapted to be securely fixed in adjusted position with relation to the teeth of the pinking wheel 19 by means of the clamping nut 54. It will be seen that the inner end of this guide plate 52 extends over the teeth of the pinking wheel and terminates closely adjacent to the inner side face of the pressure roller 50. Thus the cloth will be continuously guided to substantially the point of actual engagement by the pinking teeth and particles of waste material carried around by the pinking wheel as it rotates in the direction of feed will be deflected and interference thereby with a sharp cutting action of the pinking teeth prevented.

In the operation of the above described machine, it will be seen that as the pinking wheel 19 is rotated by the transmission of power from shaft 11 through the gears 14 and 15 and the worm gearing, said pinking wheel, by frictional contact with the periphery of member 33, rotates said member, which in turn frictionally drives the feed disk 34. This disk having gripping contact with the under side of the fabric material, in cooperation with the pressure roller 50, positively feeds said material to the teeth of the pinking wheel 19. Since the feeding disk is capable of eccentric displacement relative to the stud shaft 30 against the resistance of the resilient spider 39, it will automatically accommodate itself to variations in thickness of the materials, or in the feeding of a multiple number of plies of material to the pinking wheel. In this manner, I eliminate the additional drive gearing for the feed wheel as shown in the above-identified issued patent, and I have also greatly simplified the mounting and arrangement of the several parts constituting the automatic feed mechanism.

The horizontal mounting of the pinking wheel or cutter has many practical advantages. Thus, in comparison with the vertical mounting of the pinking wheel, it may be of relatively large diameter with a much greater number of cutting teeth. This not only results in longer life and less frequent renewals of the pinking wheel, but the horizontal arrangement of said wheel is less obstructive and affords greater visibility of the work by the operator. Also, in the vertical mounting of the cutter wheel, the cuttings or waste have a tendency to cling to the cutting teeth and accumulate to such an extent as to seriously interfere with the cutting action. In the present invention, however, due to the horizontal rotation of the pinking wheel, the greater portion of the cuttings have a tendency to continue their movement in a straight line parallel to the feed of the fabric, which is aided to a certain extent by centrifugal action in the movement of the cutter teeth in a divergent arcuate path from the line of feed. Such minor portions of the waste cuttings as may be carried around on the teeth of the cutter wheel are intercepted by the guide plate or blade 52 and deflected inwardly so that they cannot accumulate at the point of cut and interfere with the sharp cutting action of the cutter teeth. Thus a high quality product is insured.

Such particles of fine lint as may find their

way below the base plate and accumulate upon the teeth of the gear 22 will be automatically removed in the rotation of the worm 27. Thus the possibility of clogging or frictional resistance in the operation of the gearing from this cause is obviated, and the smooth uniform transmission of driving power to the pinking wheel is obtained.

From the foregoing description considered in connection with the accompanying drawing, the construction, manner of operation and several advantages of the described invention will be clearly understood. The several parts of the machine are of more or less standard or conventional form and may, therefore, be produced and cooperatively assembled at comparatively small cost, thus enabling such a machine to be profitably produced and sold at appreciably less cost to the purchaser than machines heretofore devised for this purpose.

I have herein described and illustrated a practical embodiment of the invention, which after prolonged tests, has given highly satisfactory results. It is, nevertheless, to be understood that in the form and construction of the superstructure 1, and the mounting of the pressure roller 50, as well as in other details of my present disclosure, the invention is susceptible of more or less modification or change. It is, therefore, to be understood that I reserve the privilege of incorporating the several novel features of the invention in such other alternative structural forms as may fairly be considered to be within the spirit and scope of the appended claims.

I claim:

1. In combination with a rotatably mounted trimming cutter and a work feeding member having a part movable in the plane of rotation of said cutter and a path angularly related to said plane; means, including a part actuated by said cutter, for transmitting the entire work feeding motion to said member from the cutter.

2. In combination with a rotatably mounted trimming cutter and a work feeding member having a part movable in the plane of rotation of said cutter and a path angularly related to said plane; a single element having driving connection with the cutter and directly coacting with the feeding member to transmit the entire work feeding motion to the latter.

3. In combination with a rotatably mounted trimming cutter and a work feeding member having a part movable in the plane of rotation of said cutter and a path angularly related to said plane; a driving element directly coacting with said cutter and the entire work feeding member to transmit work feeding motion to said member from the cutter.

4. In combination with a trimming cutter and work feeding member mounted to rotate in substantially right angularly related planes with respect to each other; means for transmitting the entire work feeding rotary motion to said member from said cutter.

5. In combination with a trimming cutter and work feeding member mounted to rotate in substantially right angularly related planes with respect to each other; a rotatable element having driving connection with the cutter and directly coacting with the feeding member to transmit the entire rotary work feeding motion to the latter.

6. In combination with a trimming cutter and work feeding member mounted to rotate in substantially right angularly related planes with

respect to each other; a driving member directly engaged with said cutter and work feeding member to transmit the entire rotary work feeding motion to said member from the cutter.

5 7. In combination with a trimming cutter and work feeding member mounted to rotate in substantially right angularly related planes with respect to each other; positive drive means for the cutter, and frictional drive means for said work feeding member, transmitting the entire work feeding motion thereto, operatively connected with and driven by said cutter.

10 8. In combination with a trimming cutter and work feeding member mounted to rotate in substantially right angularly related planes with respect to each other; and a rotary driving member frictionally coacting with the cutter and the feeding member to transmit the entire rotary feeding motion to the latter from the former.

15 9. In a pinking machine, a pinking cutter mounted to rotate in a horizontal plane, a member movable in tangential relation to said cutter to engage and feed the work thereto, and operating means for said work feeding member including a part directly engaged with and actuated by said cutter, to transmit the entire work feeding motion to said member.

20 10. In a pinking machine, a pinking cutter mounted to rotate in a horizontal plane, a work feeding member mounted to rotate in a vertical plane and in tangential relation to said cutter, and a drive element coacting with the cutter contiguous to said work feeding member and cooperatively associated with the latter to transmit the entire rotary work feeding motion to said member.

25 11. In a pinking machine, a pinking cutter mounted to rotate in a horizontal plane, a work feeding member mounted to rotate in a vertical plane and in tangential relation to said cutter, and a rotary driving element frictionally coacting with said work feeding member operatively engaged with and driven by said cutter, to transmit the entire work feeding motion to said member.

30 12. In a pinking machine, a pinking cutter mounted to rotate in a horizontal plane, a work feeding member mounted to rotate in a vertical plane and in tangential relation to said cutter, positive drive means for the cutter, and means, independent of said drive means, operatively connected with and actuated by said cutter for transmitting the entire rotary work feeding motion to said member.

35 13. In a pinking machine, a cutter member mounted to rotate in a horizontal plane and a work feeding member mounted to rotate in a vertical plane, positive drive means for the cutter, and a rotary driving element independent of said drive means disposed in parallel relation to one of said members, said element being engaged with and driven by said cutter and frictionally coacting with the feeding member to transmit the entire rotary feeding motion to the latter.

40 14. In a pinking machine, a cutter member mounted to rotate in a horizontal plane, a work feeding member movable in tangential relation to said cutter member, positive drive means for the cutter member including a worm gear to which said member is fixed and a driving worm meshed with said gear, and means independent of said worm gearing for transmitting the entire work feeding movement to said feeding member from the cutter member.

45 15. In a pinking machine, a base, a cutter member mounted in said base to rotate in a hori-

zontal plane, a work feeding member mounted below the base to rotate in a vertical plane and in tangential relation to said cutter member, positive drive means for the cutter member including a worm gear fixed to the cutter member and having a spindle, bearing means for said spindle on the base, a driving worm in mesh with said gear, and means between said worm gearing and the work feeding member cooperating with the latter and having driving connection 10 with the cutter member for transmitting the entire rotary work feeding motion to said feeding member.

16. In a pinking machine, a pinking member mounted to rotate in a horizontal plane and having an annular series of cutting teeth on its upper face, means for pressing the work on said teeth including a pressure roller mounted above the cutting teeth, drive means for the pinking member, and a fabric guiding blade positioned 15 in a plane perpendicular to the pinking member and in parallel relation with the line of feed of the fabric, said blade terminating at one of its ends at one side of the pressure roller and adjacent to the axis thereof.

17. In a pinking machine, a pinking member mounted to rotate in a horizontal plane and having an annular series of cutting teeth on its upper face, a pressure roller mounted above the 5 teeth of the pinking member to press the work thereon, work feeding means cooperating with said pressure roller, and a combined work-guiding and waste-deflecting blade mounted in a plane perpendicular to the pinking member and in parallel relation with the line of feed, and with one end of said blade traversing the annular series of cutting teeth.

18. In a pinking machine, a pinking member mounted to rotate in a horizontal plane and having an annular series of cutting teeth on its upper face, a pressure roller mounted above said cutting teeth to press the work thereon, drive means for the pinking member, and a member disposed above and extending at one side of said pressure roller across the cutting teeth to deflect waste materials from the path of rotation of said cutting teeth.

VICTOR J. SIGODA.
